STOVE TOP

Sam Strano and Reinold E. Gehne, St. Louis, Mo.,
assignors to Jackes-Evans Manufacturing
Company, St. Louis, Mo., a corporation of
Missouri

Application February 3, 1937, Serial No. 123,831

7 Claims. (Cl. 126—217)

This invention relates to stove tops, and with regard to certain more specific features, to a captive lid on a stove top.

Among the several objects of the invention 5 may be noted the provision of a captive lid for a stove top which in its construction shall be readily adapted to be embodied in sheet metal stoves; the provision of a lid and top of the class described which without complicated manipulation and which by simple motion may be 10 opened and precisely closed; and the provision of apparatus of the class described which may be economically formed. Other objects will be in part obvious and in part pointed out hereinafter.

The invention accordingly comprises the elements and combinations of elements, features of construction, and arrangements of parts which will be exemplified in the structures hereinafter 20 described, and the scope of the application of which will be indicated in the following claims.

In the accompanying drawings, in which is illustrated one of various embodiments of the invention,

Fig. 1 is a plan view of a stove top showing the captive lid in closed position;

Fig. 2 is a vertical section taken on line 2—2 of Fig. 1;

Fig. 3 is an enlarged vertical section taken on line 3—3 of Fig. 1; and,

Fig. 4 is a view similar to Fig. 1 showing the lid in partially open position.

Similar reference characters indicate corresponding parts throughout the several views of the drawings.

Sheet metal stoves, in order to be saleable, must be made at a low cost. For this reason such stoves are not ordinarily provided with many conveniences. For instance, the lids over 40 the firing holes, in order to be removable must be provided with handling portions which readily cool and hence they have been bulky. This prevented the use of the lid as a support for cooking utensils and the like. In the cases where the 45 lids were made suitable for supporting cooking utensils, they were very difficult to handle while hot.

Referring now more particularly to Fig. 1, there is shown at numeral 1 a flat sheet metal 50 stove top clinched to a sheet metal stove 3 (see Fig. 2). This top 1 carries the usual flue outlet 5 and a suitable brace 7 to render the top rigid. At 9 is shown a damper.

In the top 1 is a hole 11 which is provided 55 with a depending side wall 13. At the bottom

of the wall 13 is an inwardly extending flange 15. The circular recess thus formed is adapted to telescopingly receive a circular lid 17 which is formed generally flatwise and has a depending flange 19 beaded at the bottom as shown at 5 numeral 21.

The bottom of the flange 19 rests upon the flange 15 within the opening of the top 1 when the lid is in closed position.

From the above, it will be clear that the lid 10 may be applied over the opening and by gravity telescopes into place within the wall 13 and rests upon the flange 15. This construction provides a substantially flush top between the stove top 1 and the top of the lid 17. 15

In order to handle the lid 17 it is provided with a holder 23. This holder is segmental in cross section and fits into a trough-like recess 25 preferably formed along a diameter of the lid. The holder is held by fastening members 27. At 20 one end it extends to the edge of the lid and at the other end it extends over the edge and is looped as shown at 29 to form a handle which may be manipulated. The handle portion 29 extends from the side of the stove and has a 25 tendency to become cool enough to manipulate with the bare hand, if it needs not be solidly gripped for too long a period. It is therefore desirable to have the construction such that the manipulator holds the handle for the shortest 30 possible time, and/or merely pushes it about for manipulation rather than definitely gripping it tightly.

To hold the lid 17 captive to the stove, there is riveted to the stove as shown at numeral 31 35 an angle piece 33 having an extension 35 under the flange 15. Within the area enclosed by the flange, the extension 35 is provided with an opening 37 for loosely accommodating a pin 39. The pin 39 has at its upper end a head 41. The 40 pin is held to the lid by means of a foot-like member 43 which has an opening 45 accommodating the pin 39 but holding the head 41. The foot-like member 43 is held to the lid 17 by means of rivets 45 and is strengthened by being 45 clinched within the bead 21 (see Fig. 3).

At the lower end of the pin 39 is a cotter key 47 which has the effect of limiting the upward motion of the pin 39 through the openings 31. A bent portion on the lower end of the pin 39 may 50 also be used for the same purpose. In this case the bent portion should be short enough to permit it to be fed through the opening 37 by suitable angling of the lid upon assembly but which will hold the lid captive under normal move- 55

ments during use. The distance between the bottom of the member 35 and the top of key 47 is such as to permit a rise of the top 17 from the solid-line position to the dotted-line position (shown in Fig. 3). This rise is accomplished by pushing upwardly and sidewardly on the handle 29. Thus the lid may be rotated from the solid-line position shown in Fig. 1 to the solid-line position shown in Fig. 4. Further rotation may be accomplished if it is desired to further clear the opening of the lid.

To re-close the lid, it is merely necessary to push the handle 29 clockwise (Fig. 4), until the lid is centered in the opening of the stove, whereupon it will fall from the dotted-line position shown in Fig. 3 to the solid-line position shown therein.

The opening 37 accommodates the pin 39 loosely enough that the handle 29 need not be definitely gripped in order to accomplish the upward telescoping movement. Furthermore, the fit between the edge of the lid and its opening is loose enough so that upon merely pushing the handle 29 upwardly and sidewardly, there is enough camming action of the lid on the edge of the opening that it easily moves to the position shown in Fig. 4.

It will be seen from the above that there is provided a lid for a stove which has such a form and such a handle as to permit of its being manipulated hot, and at the same time the upper surface of the lid is of a form adapted to receive cooking utensils and the like. Furthermore, the lid may be readily pushed open or pushed shut with only a slight touch from the hand, and thus with minimum danger to burning of the hand. At the same time, the opened, hot lid need not be placed anywhere on the stove, or adjacent to, because it is held captive and positioned loosely at one side, ready for quick re-application to the opening whenever desired. A mere push is required to open or close. Centering is automatic and the handle 29 automatically comes back into its predetermined position at the front of the stove.

The invention has advantage over lids which hinge at right angles to the surface at which they form a part when closed, because the operator need not substantially lift the lid against gravity when opening it. Likewise, he need not resist gravity when closing the lid to prevent slamming.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. In a sheet metal stove, a sheet metal top having an opening, a downwardly extending sleeve within said opening and an inwardly extending flange from said sleeve, a sheet metal lid having a downwardly extending flange adapted to telescope said downwardly extending sleeve and rest upon said inwardly extending flange, a member connected to said top and presenting a hole inwardly of said inwardly extending flange, and a pin attached to said lid and extending through said opening, said pin being of a length adapted to permit of raising the lid from said

opening and rotating it laterally on the stove top, and means at the end of the pin adapted to hold it captive within said opening and during rotation of the lid.

2. In a sheet metal stove, a sheet metal top having a round opening, a downwardly extending sleeve within said opening and an inwardly extending flange from said sleeve, a round sheet metal lid having a downwardly extending flange adapted to telescope said downwardly extending sleeve and rest upon said inwardly extending flange, a member connected to said top and presenting a hole inwardly of said inwardly extending flange, and a pin attached to said lid and extending through said opening, said pin being of a length adapted to permit of raising the lid from said sleeve and rotating it laterally on the stove top, and means at the end of the pin adapted to hold it captive within said opening and during rotation of the lid.

3. In a sheet metal stove, a sheet metal top having an opening, a downwardly extending sleeve within said opening and an inwardly extending flange from said sleeve, a sheet metal lid having a downwardly extending flange adapted to telescope said downwardly extending sleeve and rest upon said inwardly extending flange, a member connected on the inside of said top and extending into said opening and presenting a hole inwardly of said inwardly extending flange, a pin attached to said lid and extending through said last-named opening, said pin being of a length adapted to permit of raising the lid from said sleeve and rotating it laterally on the stove top, and means at the end of the pin adapted to hold it captive within the opening and during rotation of the lid and a handle on the lid extending laterally therefrom, whereby the lid may be manipulated upwardly and sidewardly, or sidewardly and downwardly.

4. A sheet metal stove lid comprising a flat top, flange portions depending therefrom, a groove extending across the lid between said depending portions, and a handle for the lid extending from one side thereon and having fastening means lying in said groove, and means fastening said fastening means to the lid.

5. In a stove, a relatively flat top, a relatively flat lid, said top having an opening accommodating said lid, means limiting motion of the lid within the accommodating opening so that its top is flush with that of the stove, a pin depending from the lid at a peripheral point, means attached to the stove providing a hole through which said pin passes, means at the end of the pin holding it captive within said hole but permitting telescoping movement thereof in said hole to a degree permitting of lifting of the lid from the opening and rotation thereof.

6. In a stove, a relatively flat top, a relatively flat lid, said top having an opening accommodating said lid, means limiting motion of the lid within the accommodating opening so that its top is flush with that of the stove, a pin depending from the lid at a peripheral point, means attached to the stove providing a hole through which said pin may pass, means at the end of the pin holding it captive within said hole but permitting telescoping movement thereof in said hole to a degree permitting of lifting of the lid from its opening and also permitting rotation thereof, and a handle attached to the lid and extending peripherally therefrom at a point spaced from the pin.

7. In a stove, a relatively flat top, a relatively

flat lid, said top having an opening accommodating said lid, means limiting motion of the lid within the accommodating opening so that its top is flush with that of the stove, a pin depending from the lid at a peripheral point, means attached to the stove providing a hole through which said pin may pass, means at the end of the pin holding it captive within said hole but permitting telescoping movement thereof in said hole to a degree permitting of lifting of the lid

from its opening and also permitting rotation thereof, a handle attached to the lid and extending peripherally therefrom at a point spaced from the pin, said handle having an extension for fastening to the lid, said lid having a grooved recess for accommodating said extension, and fastening means between the extension and said lid. 5

SAM STRANO.
